UNITED STATES PATENT OFFICE

ALBERT E. EVANS, OF PITTSBURGH, PENNSYLVANIA, ASSIGNOR TO PITTSBURGH PLATE GLASS COMPANY, A CORPORATION OF PENNSYLVANIA

SHEET-GLASS APPARATUS

Continuation of application Serial No. 66,943, filed November 5, 1928. This application filed July 28, 1933.
Serial No. 295,368.

The invention relates to apparatus for making sheets of glass intermittently in ribbon form and annealing them, the apparatus being particularly designed for making relatively thick glass, such as plate glass or glass used in construction work, such as "Carrara" glass. In rolling thick glass, it is necessary to carry the sheet just after it is generated forward at a relatively high rate of speed in order to prevent it from sagging between the supports constituting the bed of the runway or leer, this being due to the tendency of the hot glass constituting the center of the sheet to soften the lower surface or skin of the sheet. After the sheet has set to a point where it will no longer sag, it is necessary to reduce the speed of movement of the sheet, as otherwise a leer of unduly great length is required to properly anneal and cool the glass. The reduced speed of travel of the glass through the last portion of the leer, therefore, governs the production of the apparatus, and the production of the apparatus is thus reduced to a fraction of that of the sheet rolling or generating portion. The present apparatus is designed to take care of this condition and to multiply the capacity of the leer without increasing its length. In order to accomplish this result, the leer is made in two parts, the first part, through which the glass must pass at a relatively high rate of speed, being mounted for lateral movement, and the second part of the leer being made in multiple, so that the sheets from the first part may be made to enter either one of such multiple parts. After a sheet is delivered into the second part of the leer, the speed of this part is reduced. As shown and described, the second part of the leer is made in two units, one above the other, but a greater number of units may be employed. The two units may be located in one leer chamber, or in separate leer chambers, and, if desired, they may be located alongside each other instead of one above the other, the only requirement being that the movement of the preliminary leer section be such that its outlet end may be brought into alignment with either one of the units of the second part of the leer. In using this construction, the sheets which are generated and carried rapidly through the first section of the leer, may be alternately directed into the units or sections of the second part of the leer, thus multiplying the capacity of the leer by the number of such sections. The apparatus of the present application is disclosed in my prior application, Serial Number 66,943. Certain embodiments of the invention are illustrated in the accompanying drawings, wherein:

Figure 1 is a longitudinal section through the apparatus on the line I—I of Fig. 2. Fig. 2 is a vertical section on the line II—II of Fig. 1. Fig. 3 is a plan view. Fig. 4 is a vertical section through a modification. And Figs. 5 and 6 are diagrammatic plan views of modifications.

The sheet generating apparatus at the left-hand end of the machine comprises a ring 1 supported for rotation upon the rolls 2 and 3 and a sizing roll 4 mounted in a framework 5 for swinging movement around the axis of the roll 3 as a center. The angular space 6 between the rolls 1 and 4 constitutes a pocket into which the contents of a pot or ladle is poured, any escape of glass at the ends of the pocket being prevented by means of suitable plates 7 fitting around the surfaces of the rolls adjacent their ends. The annular roll 1 is preferably made to contact with a bath of water 8 to prevent it from becoming overheated, and in order to bring it up to proper temperature before the casting operation begins, the gas burners 9 are provided. The annular roll is preferably rotated from the roll 3, such roll being driven from the electric motor 10 (Fig. 3). This motor drives a worm wheel in the casing 11 through the intermediary of the gears 12 and 13, and the end of the worm wheel carries a gear 14 which drives a gear 17 carried by the end of the roll 3. The roll 4 is provided with passages, as indicated in Fig. 1 and is cooled by circulating a flow of water therethrough. This roll is driven from the roll 3 by means of intermeshing gears upon the ends of the roll shafts.

The thickness of the glass sheet which is formed is regulated by swinging the frame 5

which carries the roll 4 about the roll 3 as an axis, this being accomplished by means of the link 19 which engages an arm 20 attached to the frame 5. This link is pivoted to a screw shaft 21 as indicated at 22 and such shaft is adjusted longitudinally by means of a worm wheel 23 operated from a worm 24 rotated by the hand crank 25. In order to hold the glass in the pocket 6 until it is desired to start the rolling operation, the stop member 26 is employed fitting between the rolls as indicated in Fig. 1 and provided with a pair of racks 27 at its ends. These racks are engaged by a pair of gears 28 carried upon a shaft 29 and operated by a crank 30. By rotating the crank, the stop member 26 is withdrawn in order to permit a flow of glass between the rolls after the pocket 6 has been filled from the ladle. In operating the apparatus, sufficient glass is supplied to the pocket 6 to form a sheet in ribbon form of the desired length.

The glass after leaving the rolls passes onto the table 31 which is hollow and water cooled so that a supporting skin is formed on the lower side of the sheet. The sheet then passes into the preliminary leer section 32. This leer section is of a length somewhat greater than that of the sheet 33 which is to be handled thereby and is constructed so that it may be moved vertically as hereinafter described. The body of the leer is constructed of suitable insulating material and is rigidly supported upon a frame-work consisting of the longitudinally extending channels 34, the transverse channels 35 and the eye beams 36, which framework in turn is carried by the lifting plunger 37. The leer section is provided with suitable gas burners 38 and has a runway for the glass in the form of a series of driven rollers 39 arranged in series extending from one end of the leer section to the other. The leer is also provided with a pair of dampers 40 and 41 for assisting in the regulating of the temperature of the leer chamber. The movement of the plunger 37 and the leer section carried thereby is governed by the application of fluid pressure through the pipes 42 and 43, a valve 44 being provided intermediate the inlet pipe 45 and the branches 42 and 43. This valve also controls an exhaust passage 46 through which the fluid at either side of the plunger head 47 may be discharged. The plunger 37 would, of course, return to the position shown due to the weight of the parts when the valve 44 is moved so as to connect the pipes 42 and 46, but the application of pressure through the pipe 43 serves to speed up this movement so that the leer section may be moved from its upper to its lower position in a minimum period of time.

The second part of the leer which receives the sheets from the section 32 is made in two units, as shown, 48 being the upper unit and

49 the lower one and each of these units is provided with a carrier or runway for the glass in the form of rollers 50 and 51. These rollers are provided upon their ends with suitable sprocket wheels and are driven by means of the sprocket chains 52 and 53. Each leer unit or section is provided with a damper 54 which may be adjusted to suit requirements, and the asbestos curtains 55 and 56 serve to close off the ends of the leer units when they are not in use. When the leer section 32 is in its lower position, the curtain 55 serves to close off the end of the upper leer unit 48 which is not in service, and when the leer section 32 is moved to its upper position in alignment with the unit 48, the curtain 56 is moved up so that it closes the end of the leer unit 49.

Mounted at one side of the leer section 32 is a standard 57 carrying a horizontal shaft 58 and such shaft is provided with a sprocket 59 driven from a sprocket chain 60 passing over a sprocket 61 (Fig. 2) carried by the end roll 51a of the leer unit 49. A vertical shaft 62 is also carried by the standard 57 and driven from the shaft 58 by means of the bevel gears 63 and 64. Secured to the side of the longitudinal channels 34 constituting the supporting framework for the leer section 32, is a standard 65 (Fig. 2) provided with a horizontal shaft 66 carrying a bevel gear 67 at its end which gear meshes with a gear 68 splined upon the vertical shaft 62, so that a drive is provided for the shaft 66 in all of the vertical positions of adjustment of the leer section 32. The shaft 66 is provided with a sprocket carrying a chain 69, and this chain passes around a sprocket wheel 70 on the countershaft 71, also carried by the channels 34. This countershaft 71 carries a second sprocket which serves as a drive for the chain 72. This chain 72 passes around a sprocket 73 carried by the channel 34 and around suitable sprockets on the ends of the roll shafts 39. A drive is thus provided for the rolls carrying the glass when the leer section is in both of its operative positions.

In operation, a sheet of glass is rolled between the rolls 1 and 4 and passed into the preliminary leer section 32, as indicated at 33. Assuming that a sheet 33a has just been fed into the leer unit 49, and it is desired to move the sheet 33 into the upper leer unit 48, fluid pressure is admitted beneath the plunger 37 causing it to rise and moving the leer section 32 upward from the position shown until the runway is in alignment with the runway of the leer unit 48. While this movement is taking place, the sheet 33 is being fed forward through the leer section 32, sufficient space being provided for this feed movement so that when the leer section reaches its upper position, the right-hand end of the sheet 33 has just reached the end of the leer section 32. The major per-

tion of the leer has its rolls following the set 51 (which are rotating at the same high speed as the rolls 36) driven at a much lower speed, so that after the sheet is delivered onto these slower moving rolls, its progress is reduced to a point where proper annealing can be secured in a leer of reasonable length. The speed of formation of the sheet and its movement over the rolls 39 and 51 preferably 10 ranges from 30 to 40 feet per minute, while the movement of the sheet in the major portion of the leer following the rolls 50 and 51 is preferably about four feet per minute. After the sheet has been moved into the leer unit 48, the preliminary leer section is lowered to its starting position, this being accomplished by exhausting the fluid from beneath the plunger through the pipes 42 and 46, while pressure is admitted above the plunger head through the pipe 43. In this manner, sheets from the preliminary leer section are alternately supplied to the leer units 48 and 49 so that the capacity of the apparatus is doubled.

Fig. 4 illustrates a modification of the construction of Fig. 1, wherein the leer sections or units consisting of the sets of rolls 74 and 75 are located in a single leer chamber 76 instead of having a dividing wall, such as the wall 77 of the Fig. 1 construction, therebetween. This is a cheaper construction than that of Fig. 1 construction. As heretofore indicated, the invention is capable of embodiment in a wide variety of forms, all that is necessary being the plurality of secondary leer units used in conjunction with a preliminary leer section or runway whose outer end is adapted to be brought into alignment with any one of the secondary leer units.

Figs. 5 and 6 show diagrammatic modifications of the broad idea involved. In the Fig. 5 construction 78 is the primary leer section mounted for lateral movement on the track 79, so that it may be shifted laterally, so as to align with any one of the secondary leer sections 80, 81, 82, the dotted lines indicating the other positions of the section 78. The rolling mechanism 83 is preferably the same as in the Fig. 1 construction and suitable power means are provided for shifting the section 78 laterally.

In the Fig. 6 apparatus, the primary leer section 84 is mounted upon a turntable to swing around a vertical axis located at 85 so that the section may be brought into alignment with the radially directed secondary leer sections 86, 87, and 88, the dotted lines indicating the other positions of the section 84. The rolling mechanism 89 is preferably the same as in the Fig. 1 construction and suitable power means are provided for shifting the turntable about the axis 85. If desired, the secondary sections of the leer may be of the oven type in which the glass is kept stationary instead of the tunnel type,

or these secondary sections might be in part of the tunnel type and in part the oven type. What I claim is:

The combination with a pair of rolls for forming sheets of glass successively in ribbon form from bodies of molten glass, a vertically movable runway extending forwardly from the rolls and provided with means for carrying the glass ribbons therealong, and a plurality of roller leer sections or units in advance of the runway, one above the other, and means for operating the rolls of the runway and those at the entrance of the leer at a relatively higher speed than the rolls following the entrance rolls and extending through the body of the leer, the said runway being mounted so that its outlet end may be brought into alignment with any one of the leer sections or units.

In testimony whereof, I have hereunto subscribed my name this 17th day of July, 1928.

ALBERT E. EVANS.
